UNITED STATES PATENT OFFICE.

FRANKLIN B. WARRING, OF SAN JOSE, CALIFORNIA, ASSIGNOR TO CATON'S FOUNDRY AND MACHINE COMPANY, OF SAN JOSE, CALIFORNIA.

HYDROCARBON-FEEDER FOR EXPLOSIVE-ENGINES.

SPECIFICATION forming part of Letters Patent No. 709,428, dated September 16, 1902

Application filed April 3, 1901. Serial No. 54,152. (No model.)

To all whom it may concern:

Be it known that I, FRANKLIN B. WARRING, a citizen of the United States, residing at San Jose, in the county of Santa Clara and State of California, have invented certain new and useful Improvements in Automatic Hydrocarbon-Feeders for Explosive-Engines; and I do hereby declare the following to be a full, clear, and exact description of the invention, such as will enable others skilled in the art to which it appertains to make and use the same.

This invention relates to gas or vapor engines, sometimes termed "explosive-engines," and has special reference to an improved feeding device or valve for the oil or hydrocarbon which provides positive and reliable means for automatically feeding the liquid in a quantity suited to the work or load imposed upon the engine.

To this end the invention contemplates an oil-feeding device or valve designed to be associated with the suction supply-pipe of the engine directly, or indirectly with such pipe through the carbureter or other form of generator which may be utilized in connection with the engine and from which the gaseous or explosive mixture is drawn through the said suction supply-pipes. In this special use of the device or valve the same has in view the provision of simple and reliable means controllable by the suction of the engine whereby the necessary supply of hydrocarbon will be regulated automatically according to the load under which the engine is working.

A further object is to provide a construction of feeder or valve which under normal conditions will remain completely closed to cut off the supply of hydrocarbon from the engine or the carbureter associated therewith.

With these and many other objects in view, which will more readily appear as the nature of the invention is better understood, the same consists in the novel construction, combination, and arrangement of parts herein-after more fully described, illustrated, and claimed.

The essential features of the invention are necessarily susceptible to some modification without departing from the spirit or scope thereof; but the preferred embodiment of the

improvements is shown in the accompanying drawings, in which—

Figure 1 is an elevation showing the improved feeding device or valve applied for use in the preferred way—namely, in connection with the generator or carbureter for the engine. Fig. 2 is an enlarged sectional view of the complete feeding device, or "valve," as it is sometimes termed.

Like numerals of reference designate like and corresponding parts in the several figures of the drawings.

As already stated, the feeding device may be associated directly with the suction supply-pipe of an engine, or, in other words, with the air-supply pipe of that type of engines which during the action thereof draw in a mixture of air and hydrocarbon, or the device may be utilized in connection with the carbureter or generator, which may be fitted to the suction supply-pipe of the engine. In either of these adaptations of the feeding device the latter is necessarily included in the suction or draft of the engine, so that the same will be controllable by the said suction or draft. However, for purposes of illustration the feeding device or valve is shown in the drawings as coupled directly to a generator or carbureter 1 of the type in which the oil or hydrocarbon is vaporized and mingled with the air, which is drawn into the engine through the suction supply-pipe 2 thereof. Of course the feeding device or valve will be applicable to any type of carbureter; but in the adaptation shown the oil-delivery neck or port 3 of the feeding device is suitably coupled to the casing of the carbureter 1 to provide for delivering oil into the carbureter, while at the same time being in communication with the air-space thereof.

In its general organization the oil-feeding device comprehends a main casing 4, which may be properly termed the "valve-casing" the same preferably being of an elongated cylindrical form. The said valve-casing 4 is provided at a point intermediate the ends thereof with an interior annular diaphragm 5, provided with a valve-seat opening 6, preferably beveled to register with the correspondingly-beveled portion of the feed-valve or valve-disk 7, carried by the reciprocating

valve-stem 8, arranged longitudinally of the casing. The said interior diaphragm 5 divides or separates the interior of the valve-casing into two separate chambers, designated, respectively, as the oil-supply chamber 8^a and the vacuum cylinder or chamber 9, which latter cylinder or chamber is directly in communication with the oil-delivery neck or port 3, and at one end of the vacuum cylinder or chamber 9 the casing 4 is provided with an end opening 10 and an inwardly-projecting flange 11, forming the said opening.

Within the vacuum chamber or cylinder 9 there is slidably arranged a valve-actuating piston 12, snugly registering with the inner wall of the vacuum-chamber, so as to have a piston action exclusively, and the said piston is fitted on the valve-stem 8, contiguous to one end thereof, against a bearing-shoulder 13, provided thereon. Contiguous to said bearing-shoulder the valve-stem 8 is provided with a threaded portion, receiving a binding-nut 14 for detachably clamping the piston in place. The extremity of the stem 8 adjacent to the piston and the fastening means therefor has connected thereto one end of a coiled retracting-spring 15, the other end of which spring is connected to a stationary angled supporting-bracket 16, which is rigidly fastened in any suitable manner directly to the casing 4 or to an equivalent fixed support. The end of the stem 8 opposite the spring connection therewith is guided in its movement within the guiding-bore 17 of the valve-stem guide 18, constituting a closing-head for one end of the valve-casing, and the outer portion of whose bore is threaded at 19 to receive a stop-screw 20, longitudinally alined with the stem 8 and adjustable, so as to vary the amplitude of movement of the stem 8 as conditions may require.

The oil-supply chamber 8^a at one side of the interior diaphragm 5 is formed with an inlet-port 21, with which is connected the supply-pipe 22, leading to a storage-tank or other source of supply for the gasoline or other hydrocarbon.

Under normal conditions when the engine is not working the tension of the spring 15 is sufficient to retract the valve-stem to the limit of its movement in one direction, thereby closing the valve 7 within the seat 6, and thus cutting off the flow of oil from the oil-supply chamber 8^a. When the engine creates a draft or suction within the suction supply-pipe 2 thereof, a partial vacuum or rarefaction is necessarily caused within the vacuum-chamber 9, thereby permitting the atmosphere to exert a pressure upon the outer side 60 of the valve-actuating piston 12, thus moving such piston inward and causing an unseating of the valve 7. This valve is of mate-

rially smaller area than the piston 12, so as not to interfere with this operation, and immediately upon being opened away from the seat 6 a supply of hydrocarbon is permitted to flow through the chamber 9 and the neck or port 3 into the carburetor or generator. When the suction or draft from the engine ceases during the period when the engine is not drawing in the gaseous mixture, the spring 15 will retract and effect a closing of the valve. Thus the operation is entirely automatic and the supply of oil is practically regulated according to the suction or draft of the engine.

From the foregoing it is thought that the construction, operation, and many advantages of the herein-described feeding device or valve will be readily understood without further description, and it will also be understood that various changes in the form, proportion, and minor details of construction may be resorted to without departing from the spirit or scope of the invention.

Having thus described the invention, what I claim as new, and desire to secure by Letters Patent, is—

1. The combination with a carburetor of an engine, of a casing having separate interior oil-supply and vacuum chambers, the latter having connection with the carburetor and having also an end opening, a valve-stem movable in said casing, a valve carried by said stem and controlling a port between the oil-supply and vacuum chambers, a piston on said stem within the vacuum-chamber, a retracting-spring connected with the said stem, and a guide for the opposite end of the valve-stem, all substantially as and for the purpose specified.

2. A feeding device of the class described comprising a valve-casing having separate interior oil-supply and vacuum chambers, the oil-supply chamber having an inlet-port, and the vacuum-chamber having an oil-delivery port, and also having an end opening and a guard-flange, a longitudinally-movable valve-stem carrying a feed-valve controlling communication between the two chambers, a valve-actuating piston fitted upon the stem and working within the vacuum-chamber, a supporting-bracket carried by the valve-casing at one end, a spring having a connection with said bracket and also with the valve-stem, a guide for the front end of said stem, and an adjusting device for limiting the movement of the stem carried by said guide.

In testimony whereof I affix my signature in presence of two witnesses.

FRANKLIN B. WARRING.
